PORATION

MEANS FOR PRODUCING ARTICLES FROM GRANULAR OR PLASTIC SUBSTANCES

Application filed December 29, 1927, Serial No. 243,412, and in Sweden May 29, 1926.

In making casting molds from sand or other granular material, it is hitherto a common praxis to subject the casting box or flask to a strong shaking movement in a vertical direction. This has generally been performed in such a manner that the downward movement has been suddenly interrupted, and especially at the shocks thereby caused the grains have been packed together in the desired manner. The total movement has necessarily been rather large, in order to produce a sufficiently strong shock, and during the major part of this movement no real packing of the grains has taken place. A close examination of this process therefore shows it to be of rather small efficiency.

According to the present invention, the mold or casting box together with the granular material, such as sand contained therein, is subjected to rapid vibrations for packing the said material together. It appears at the first thought that such vibrations which involve alternating, practically equal forces acting on the grains in opposite directions, would not cause an efficient packing of the grains. The experience, however, proves that a much greater force is necessary for loosening the grains after they have once been squeezed in between each other by wedge action, than for the said squeezing in, and the result will be that practically every change in the direction of movement will increase the packing effect, if the vibration process is used, whereas in the old shaking process a packing takes place only when the direction of movement is reversed from downward to upward. Theoretically, if the maximum retardation is the same and other circumstances equivalent in both cases, the proportion between the working speeds of the two processes would therefore be about twice the proportion between the frequencies. In practice it has also been found that a very considerable saving of time is obtained. Further it is possible with this process to manufacture much smaller cores, molds and the like than by the shaking process.

It is advisable to subject the sand or other material to a light pressure during the vibration. For smaller objects, the said pressure can be exerted by hand; for larger objects,

a press plate or the like may be employed, serving as a counter support against the vibratory motion.

The frequency of the vibrations employed may vary within rather wide limits. As a lower limit, ten complete cycles per second may be chosen, this being at any rate considerably more than has been used in the shaking process, that is, about five cycles per second as a maximum. Generally it is, however, advisable to employ between 30 and 100 cycles per second. The vibrations may be either single, reciprocating in a certain direction, or complex, alternately in various directions forming angles with each other. They may also, if desired, be of a more irregular character. The introduction of the sand or other material may take place either before the beginning of the vibrations or gradually during the said vibrations and in either case be made by any kind of filling means.

The invention is applicable also in making keramic and cementatory objects, such as pipes, bricks and the like to be produced in a mold, said mold and the cement, clay or other suitable material contained therein being subjected to vibrations in the manner set forth.

The invention also relates to means for executing the process, comprising a movable table or other support for the flask or casting box carried by one or more mechanically or electrically driven vibrators adapted to set the support with the objects carried thereby in vibrations. If desired, the vibrators may instead be carried by the table.

In the accompanying drawing, two embodiments of a machine for carrying the process into effect are illustrated. Fig. 1 shows a molding machine in elevation, partly in section and Fig. 2 shows a detail of a modified form of the upper portion of the machine shown in Fig. 1 also in elevation and partial section.

Referring to Fig. 1, a frame 1, which may be tiltable in a stand 2 in a known manner, is provided at its lower part with guiding grooves 3 in which a vibrator cylinder 4 containing a piston 12 is movable up and down. The cylinder carries at its top a table 5 for

the casting box 6. Placed on the latter is a separate filling hopper or frame 7 which may be partially or totally filled with sand or corresponding material during the operation.

5 The table 5 is carried by the cylinder 4 by means of bolts 8 secured to the former and traversing guide holes in projections 9 on the cylinder. The bolts are surrounded by springs 10 which normally press the table 5 downwards into its lowest position. By means of set screws 11, the bolts 8 may be locked to the guiding projections 9 so that the table is held firmly to the cylinder. The resilient connection (with loose set screws) 15 is used for big objects, the rigid connection for small ones, for which the deformation of the material provides for sufficient vibrations.

For accelerating the compression of the material to be molded, especially in the upper 20 layers, a press plate 13 may be used, which for instance may be lifted by means of a hand wheel 14, and which according to Fig. 1 is presumed to be so heavy that its own weight is sufficient for the compression, so that no 25 adjustment is necessary for packing the sand. For molding small objects, the said press plate may not be necessary, as a pressure by hand may be sufficient. For such cases, the upper portion of the frame 1 may be swung 30 to the side on a hinge 15. With the machine illustrated, two or more objects placed on one another may be molded, for instance the two halves of a divided casting mold or core.

The cylinder 4 is, as already stated, somewhat movable in the frame in a vertical direction and resiliently supported in the same by means of springs 16 surrounding bolts 17. This movement can be arrested by means of 35 latches 18 which is especially desirable when the frame shall be tilted for extracting the mold or core.

In the modified embodiment of the machine shown in Fig. 2, the plate 13 is carried by means of bolts 19 and springs 20 by a vibrator 45 cylinder 21, which in its turn is carried by the piston rod 22 of a cylinder 23 mounted on the frame and serving to exert pressure during the molding and to lift the plate (to which the molded object or part thereof may be 50 fixed) after the said operation.

What I claim is:—

1. A machine for making molds from granular substances, comprising a frame, a vibrator resiliently carried by said frame, and a mold support carried by said vibrator.

2. A machine for making molds from granular substances, comprising a frame, a vibrator resiliently carried by said frame, a device 60 for locking said vibrator rigidly to said frame, and a mold support carried by said vibrator.

3. A machine for making molds from granular substances, comprising a frame, a vibrator 65 resiliently carried by said frame, a mold

support carried by said vibrator, and means for compressing said granular substances.

4. A machine for making molds from granular substances, comprising a frame, a vibrator resiliently carried by said frame, a mold 70 support carried by said vibrator, and means for exerting vibratory pressure on objects carried by said support.

5. A machine for making goods from granular or plastic substances, comprising a frame, a vibrator resiliently carried by said frame, and a mold support connected to said vibrator.

6. In a machine for making molds from granular materials, a frame, a mold support 80 on said frame, a casting box on said support for receiving granular material, resiliently mounted means for applying vibratory movement to said mold support and means for simultaneously applying pressure to the granular material in said casting box.

7. In a machine for making molds from granular materials, a frame, vibrator mechanism resiliently secured to said frame, and a mold support resiliently secured to said vibrator mechanism.

8. In a machine for making molds, in combination, a frame, a vibrator, and a mold, means for yieldingly supporting the vibrator on said frame, and means for resiliently 95 mounting said mold on said vibrator.

In testimony whereof I affix my signature.
KNUT GUNNAR WALLENTIN PETTERSSON.
